UNITED STATES PATENT OFFICE.

HENRY M. LANE, OF DETROIT, MICHIGAN.

CONVEYING MECHANISM.

1,266,828.

Specification of Letters Patent. Patented May 21, 1918.

Application filed September 22, 1917. Serial No. 192,755.

To all whom it may concern:

Be it known that I, HENRY M. LANE, a citizen of the United States, residing at Detroit, in the county of Wayne and State 5 of Michigan, have invented certain new and useful Improvements in Conveying Mechanism, of which the following is a specification.

This invention relates to conveying mechanism, and it comprises a trolley frame and a ladle frame carried thereby and capable of being lowered to receive a ladle, and to facilitate pouring of the molten metal from the ladle into molds, and capable of being 15 elevated above the heads of the workmen when in motion, the said mechanism comprising means for supporting a ladle and an operator's cage, tilting means for the ladle and elevating and traversing means; 20 all as hereinafter more fully set forth and as claimed.

Various methods have been proposed for conveying molten metal about a foundry, but so far as they involve power actuated 25 means they have generally proved unsatisfactory. In a satisfactory machine to eliminate danger to workmen, it is necessary to provide something which can be lowered for the purpose of engaging and disengaging 30 ladles and for pouring metal into molds; and means for rigidly holding ladles in position. The machine must be under positive control of the operator of the machine at all times.

35 In the present invention, I employ crane means adapted to travel upon an overhead rail or rails, the crane means comprising a trolley frame carrying propelling means and a ladle frame, capable of vertical movement with respect to the trolley frame, suitable means being provided for raising and lowering the ladle frame. The ladle frame has an operator's cage arranged therein and is provided with means for rigidly holding 40 a ladle, together with means for tilting the ladle to pour its contents. The traversing means, the elevating means, the ladle support, and the means for tilting the ladle are all operable from the cage, placing every 45 part of the machine under the direct control of the operator and minimizing the possibility of injury to the workmen, the ladle frame being elevated above the heads of the workmen before moving from place to place 50 and being lowered for the purpose of en-

gaging and disengaging a ladle, or for pouring the contents into a mold.

In the accompanying drawing I have 60 illustrated an advantageous embodiment of my invention,

In this showing:

Figure 1 is a side elevation of the invention;

Fig. 2 is an end view of the structure of 65 Fig. 1;

Fig. 3 is a horizontal sectional view on line 3—3 of Fig. 1;

Fig. 4 is a detail view of the ladle supporting means and of lever mechanism for operating the same;

Fig. 5 is a side elevation showing a slight 70 modification of the structure of Fig. 1;

Fig. 6 is a detail fragmentary view at right angles to the showing of Fig. 5 of means for operating the ladle; and

Fig. 7 is a similar view showing the manner of engaging the ladle by the supporting member.

The trolley frame A is provided with 80 trolley wheels 1 mounted in hangers 2 carried by the frame and adapted to travel upon the overhead rail B. A motor 3 is carried upon the trolley frame and drives the machine through gears 4 applying power to one of the trolley wheels 1.

A ladle frame C is suspended from the trolley frame A by ropes or cables 5 which pass over pulleys 6 and are wound around the drums 7. The drums 7 are mounted upon the shaft 8 of the motor 9 which is 90 mounted upon the trolley frame. The ladle frame C is provided with a cage 10 in which is arranged a seat 11. Controller handles 12 and 13 are arranged within the cage and these handles are connected to tubes or rods 95 14 and 15 which have sliding engagement with hollow shafts 16 and 17. The shafts 16 and 17 are, respectively, connected to controllers 18 and 19 carried by the trolley frame A, the controller 18 being connected 100 with the motor 3 and controller 19 with motor 9 (not shown). The frame A is provided with depending guides 20 in which the frame C is adapted to move.

The ladle 21, used in connection with this 105 machine, is provided with trunnions 22 and 23 for the purpose of engaging with the arms 24 which are pivotally connected to the ladle frame C. Each of the arms 24 is provided with an opening 25 through which the 110

trunnions pass when the arms are in engagement with the ladle. A lever 26 is pivotally mounted on a bracket 27 carried by the ladle frame C and links 28 are connected to each end of the lever 26 and to the arms 24. A rod or lever 29 is connected to the lever 26 at one end, and at its opposite end to an operating lever 30 which is pivotally mounted upon the ladle frame and located within the 10 operator's cage.

One of the arms 24 is provided with a gear wheel 31 journaled in the opening 25 and the gear wheel is adapted to receive the trunnion 23, the trunnion and gear wheel 15 being keyed together. A small gear or pinion 32 is mounted upon a shaft 33 journaled in the arm 24 and meshes with the gear wheel 31. A shaft 34 is journaled in the frame of the cage and is provided with an 20 operating wheel or handle 35 upon its inner end, the shafts 33 and 34 being connected by a flexible shaft 36 or equivalent mechanical means such as a universal joint (not shown).

25 The construction of the form shown in Figs. 5, 6 and 7 is very similar to that previously described, but in this instance the arms 24 are provided with pins 36' traveling in curved slots 37. The arms are normally 30 stationary at the lower end of the slot 37 and in position to engage the trunnions 22 and 23. The arms are provided with hooks 38 upon their ends for engaging the trunnions and the trunnion 23 carries a gear 35 wheel 39 which meshes with a pinion or smaller gear wheel 40 mounted on a shaft 41 carried by one of the arms 24. The shaft 41 is journaled in an enlarged bearing 42 in the cage 10 and is provided with a hand- 40 wheel 43. It may be advisable in some cases to have the tilting gears attached to the ladle and use a socket shaft to connect with the handwheel in the cage, but this is a detail of construction and does not require illustration.

45 The operation of the machine is as follows:—Power is supplied from the motor 3 which drives one of the wheels 1 through the medium of gears 4. The motor is controlled 50 by the controller 18 which is regulated by the handle 12 in the operator's cage. This handle rotates shaft 14 which in turn rotates hollow shaft 16. When it is desired to pour molten metal into a mold or to dis- 55 engage an empty ladle and engage a full one, the ladle frame C is lowered through the medium of the handle 13. Rod 15 and the hollow shaft 17 operate the controller 19 which starts the motor 9 unwinding the 60 cables 5 from the pulleys 7. To raise the ladle frame, the motor is operated in a reverse direction. The ladle frame is guided in its vertical movement by the guide rods 20.

65 The arms 24 engaging the ladle trunnions 22 and 23 are released through the operation

of the lever 30 moving the rod 29, the lever 26 and the links 28. When the arms 24 are in engagement with the ladle trunnions 22 and 23, the ladle is rigidly held and prevented from tipping by the gear wheel 31 70 which is keyed to the trunnion 23. When it is desired to pour the metal, the ladle may be readily tilted through the medium of the gears 31 and 32 which are operated by movement of the handle 35 within the operator's cage, rotating the shaft 33, 34 and 36. 75

In the modified form of the invention shown in Figs. 5, 6 and 7 the controllers 18 and 19 are governed by the cords or ropes 44 to allow the machine to be moved from place 80 to place or to lower the ladle frame C, as the case may be. The arms 24 supported in the curved slots 37 normally engage the ladle trunnions and when it is desired to remove the ladle 21 the arms are moved out of engagement with trunnions 22 and 23 by an attendant. The bearing 42 is made enlarged to permit lateral movement of the shaft 41 when the arm 24 is disengaged from the ladle trunnion 23. It will be seen from 85 the above description that I have provided a machine in which molten metal can be readily conveyed about a foundry over the heads of the workmen in a ladle rigidly supported, and can be lowered at the will of the 90 operator to allow the metal to be poured into a mold or to disengage an empty ladle. A very important feature of the invention is the arrangement of parts whereby all controlling elements are under the direct control 95 of the operator riding in a cage mounted in the ladle frame and moving up and down with the ladle.

What I claim is:—

1. A ladle crane comprising a ladle, means 105 for detachably supporting the ladle, means for tilting the ladle, and an operator's cage carried by the crane in fixed relation to the ladle.

2. A ladle crane comprising a ladle, ladle- 110 supporting means, an operator's cage carried by the crane in fixed relation to the ladle supporting means, means for elevating the ladle supporting means and cage, and traversing means for the crane.

3. A ladle crane comprising a ladle, ladle- 115 supporting means, an operator's cage carried by the crane in fixed relation to the ladle supporting means, means for elevating the ladle supporting means and cage, traversing means, and means for tilting the ladle.

4. A foundry appliance comprising a ladle having lateral supporting elements, pivoted means for engaging said supporting elements, an operator's cage in fixed relation to 120 the ladle engaging means, and means operable from the cage to control said pivoted engaging means.

5. A foundry appliance comprising a ladle having lateral supporting elements, pivoted 125

means for engaging said supporting elements, elevating and traversing means, an operator's cage in fixed relation to the ladle engaging means, and means operable from 5 the cage to control said pivoted engaging means.

6. A ladle crane comprising a ladle, ladle supporting means, elevating and traversing means, an operator's cage carried by the 10 crane in fixed relation to the ladle-supporting means and means for independently controlling the elevating and traversing means.

7. A ladle crane comprising ladle supporting means, elevating and traversing means, 15 an operator's cage carried by the crane in fixed relation to the ladle-supporting means, means operable from the cage for tilting the ladle, and means for independently controlling the elevating and traversing means.

20 8. A ladle crane comprising a trolley frame, a ladle frame, means for elevating the ladle frame in the trolley frame, ladle supporting means carried by the ladle frame, and an operator's cage within the said ladle 25 frame and in fixed relation with said ladle supporting means.

9. A ladle crane comprising a trolley frame, a ladle frame, means for elevating the ladle frame in the trolley frame, ladle

supporting means carried by the ladle frame, 30 means for tilting the ladle, and an operator's cage within said ladle frame and in fixed relation with said ladle supporting means.

10. A ladle crane comprising a trolley frame, a ladle frame, means for elevating the 35 ladle frame in the trolley frame, ladle supporting means carried by the ladle frame, an operator's cage within said ladle frame and in fixed relation with said ladle supporting means, and means operable from the cage for 40 tilting the ladle.

11. A ladle crane comprising a trolley frame, a ladle frame, means carried by the ladle frame for supporting the ladle, an operator's cage within the ladle frame and 45 in fixed relation to the ladle supporting means, and means operable from the cage for elevating the ladle frame.

12. A foundry appliance comprising a ladle and a frame, elevating and traversing 50 means therefor, an operator's cage within the frame, pivoted arms for engaging the ladle, and an operating lever pivoted in the cage and connected to the pivoted arms.

In testimony whereof, I affix my signature 55 hereto.

HENRY M. LANE.
